DEEP-DRAWING OF SHEET METAL

Charles Joseph Rhodes, Wakefield, England

Application February 4, 1950, Serial No. 142,404

Claims priority, application Great Britain
November 18, 1949

3 Claims. (Cl. 113—46)

1

This invention relates to improvements in or relating to the deep-drawing of sheet metal.

Presses are known in which a female die carried by a ram co-operates with a second die supported on the bed plate of the press, and in which the second die comprises a former surrounded by an annular member, which latter is supported by a pressure plate beneath the bed of the press, the pressure plate being connected by rack-and-pinion means to the former so as to raise the former against the action of a compression return spring as the annular member and the pressure plate are depressed by the descending upper die during the drawing operation.

Difficulty is experienced in adapting a press of this known kind to a deep-drawing operation in which a sheet metal blank is first drawn by the former through a drawing ring carried by the mould of the female die, and then, leaving the drawing ring, is drawn by the former through one or more reducing rings within the female die. Since pressure is transmitted from the female die through the blank to the annular member, and thence to the former, the blank is gripped so tightly between the female die and the annular member that it suffers undue strain in being pulled from between these two parts. The use of a compression return spring also prevents the stroke of the former being extended at will to suit deeper female dies.

According to this invention a press for the deep-drawing of sheet metal comprises a ram, carrying a female die, reciprocable with a working and a return stroke towards and away from a co-operating die, a former in the co-operating die adapted to be projected therefrom into the female die during the working stroke, an annular member surrounding the former and adapted to be depressed by the female die during the working stroke, and motion-transmitting means, independent of the annular member, operable during the working stroke of the ram to transmit from the ram to the former a motion opposite in direction to that of the ram.

In the press of the invention, motion is transmitted from the ram to the former independently of the annular member and the pressure with which the blank is gripped between the female die and the annular member is therefore reduced, so that the metal blank undergoes no undue strain.

Preferably the said motion-transmitting means are adjustable to become operative to transmit motion when the female die reaches a desired, predetermined distance from the annular member during the working stroke.

2

Preferably the said motion-transmitting means are operable during the return stroke of the ram to transmit from the ram to the former a motion opposite to that of the ram, until the former is about to leave the female die and the said motion-transmitting means are also operable during the return stroke of the ram to return the annular member towards its starting position. With this arrangement the compression return spring for the former may be replaced by spring means urging the former away from and the annular member towards the ram. The stroke of the former may then be lengthened or shortened as desired to suit female dies of varying depths.

One embodiment of the invention will now be described by way of example with reference to the accompanying drawings, in which:

Fig. 1 is a side elevation of a deep-drawing press according to the invention, the side plate being broken away for clarity.

Fig. 2 is a plan view of the press in Fig. 1, the top cover plates being removed and the bed and bed-plate of the press shown in section for clarity.

Fig. 3 is an enlarged sectional plan of the press in Figs. 1 and 2 showing the arrangement of the parts of the press at the bottom of the working stroke, the driving mechanism being omitted.

Fig. 4 is a section on line A-B in Fig. 3, and Fig. 5 is a fragmentary sectional view of a modified form of female die.

Referring now to the drawings and more particularly to Fig. 3, in which only such parts of the press are shown as are necessary for the proper understanding of the invention, an adjustable-stroke ram 1 has a female die 2 exchangeably secured thereto, the ram being horizontally reciprocable with a working and a return stroke towards and away from a co-operating die 3 secured to the bed-plate 4, which is supported by the bed 5 of the press. The female die 2 comprises a die base 2a, an annular body portion provided with diametrically opposite windows 2b through the lower of which the extruded article falls downwards out of the female die when extrusion is completed. A draw-ring 2c constitutes the mouth of the female die. A reducing or ironing ring 2d and a stripper ring 2e which abut each other, are interposed between the draw-ring 2c and the annular body portion. The drawing-ring 2c, the ironing or reducing ring 2d, the stripper ring 2e, the annular body portion and the die base 2a are secured together by bolts 6.

The co-operating die 3 comprises a base

mounted on the bed-plate 4, the bore of the die base being adjacent a large opening 7 in the bed-plate, and an annular member or pressure bush 8 slideable within the bore of the die-base, and free to pass through the opening 7 in the bed-plate during the working and return strokes of the ram. A horizontal former spindle 9 having a working end 9a exchangeably screwed into the main spindle 9 is slideably carried by a fixed bearing 10 at its end remote from the ram and by a fixed bearing 11 intermediate its ends, the bearings 10 and 11 being rigidly secured to the frame of the press. The former spindle 9 is slideable within the bore of the pressure bush 8 and within the bore of the female die 2.

A transmission member in the form of a pressure plate 12 is slideably mounted on the former spindle and bears against the end of the pressure bush remote from the ram through an intermediate pressure block 13, secured to the pressure plate.

The former spindle 9 is reduced in diameter at its end remote from the ram and carries a member 14 concentrically therewith, the member 14 having a set of rack teeth 15 on opposite sides thereof transversely of the central axis of the spindle and rigidly secured to the spindle by a nut 16 and a locknut 17.

Pinions 18 are rotatably mounted on spindles 19 fixedly carried by a pinion bracket 20 (Fig. 4) which latter is rigidly secured beneath to a pinion bracket support 21 located transversely of the former spindle axis and rigidly secured at each end to side plates 22 and 23 of the press. A cover plate 24 (Fig. 4) is provided on top and is supported at each end by the side plates 22 and 23 and affords easy access to the parts of the press described above.

The pinions 18 are spaced transversely of the former spindle 9 and engage with the rack teeth 15 on either side of the member 14 and also engage with rack teeth on the inner surfaces of two parallel spaced rack-members 25 which are each pivotally secured at one end thereof to the pressure plate 12 by pins 26. The rack members 25 are kept in engagement with the pinions 18 by rollers 27 engaging with the outer surfaces of the rack members, the rollers being rotatably mounted on spindles 28 fixedly carried by the pinion bracket 20. The rack members 25 are each provided on their outer surfaces near their ends adjacent to the pressure plate, with a stepped portion, which latter is under-cut to form a projection 29a, having a vertical abutment face 30 and a second projection 29b having an inclined abutment face 31. The ends 32 of the rack members 25 remote from the pressure plate are bent outwards at right angles and are provided with openings 33.

The ram 1 is connected to the bent ends 32 of the rack members 25 through two parallel spaced adjustable turnbuckle links 34 pivotally connected to the ram at one of their ends by pins 35, the other ends being screw-threadedly connected to motion-transmitting members 36 which pass through openings 37 in the bed-plate 4 and an opening 38 in the bed of the press, and extend part-way along the press parallel to the axis of the former spindle 9 and adjacent the outer surfaces of the rack members 25. The ends 39 of the members 36 are bent outwardly parallel to the ends 32 of the rack members 25 and are each provided with a slot 40. The ends 39 and 32 are inter-connected

by close wound helical springs 41 pivotally connected to the ends 39 of the members 36 by pins 42 and adjustably secured to the ends 32 of the rack members 25 by means of a screw 5 threaded portion passing through the openings 33 and locked in position by screw-threaded nuts 43.

The members 36 are provided on their inner surfaces adjacent the outer surface of the rack members 25 with stepped portions 44, having straight abutment faces 45 and inclined abutment faces 46, the abutment faces 45 and 46 corresponding to the abutment faces 30 and 31 of the undercut portion of the rack members 25. Ramps 47 are provided on the outer surfaces of the members 36 intermediate their ends and cam rollers 48 rotatably mounted on pins 49 secured to the bed of the press at either side thereof engage with the outer surfaces of the members 36. The rollers 48 urge the members 36 to engage with the rack members 25 when the ram reaches a predetermined point in its working stroke and assume the positions shown in Fig. 3 when the ram is at the bottom of its working stroke.

The deep-drawing press described above functions as follows:

When the ram 1 is at the top of the return stroke, i. e. in the rest position, the working end 9a of the former spindle 9 and the end of the pressure bush adjacent the female die 2 are flush with the end of the base of the co-operating die 3 and a space exists between the mouth of the female die 2 and the co-operating die 3 to permit the insertion of a metal blank. The turnbuckle links are adjusted so that motion will be imparted to the former spindle 9 in the opposite direction to the motion of the ram, through the motion-transmitting members 36, the springs 41, the rack members 25, the pinions 18 and the members 14 mounted on the spindle 9, when the female die 2 carried by the ram 1 reaches a predetermined distance from the pressure bush 8.

As the ram 1 carries the female die 2 towards the cooperating die 3, the ramps 47 engage the rollers 48 and swing the motion-transmitting members 36 inwards, so that the steps 44 enter the undercut portions on the outer sides of the rack members 25. When the spacing between the female die 2 and the pressure bush 8 has been reduced to the above-mentioned predetermined distance, the abutment faces 45 come into abutment with the abutment faces 30 on the rack members 25. Drive is then positively transmitted from the ram through the transmission members 36, rack members 25, pinions 18 and rack members 14 to the former spindle 9, independently of the pressure bush 8. The female die 2 is thus positively spaced from the pressure bush 8 as the blank is drawn by the former 9 through the draw-ring 2c of the female die 2, and the drawn blank can readily escape from between the positively spaced faces of the parts 8 and 2c into the interior of the female die, where it is drawn by the former 9 through the reducing ring 2d and the stripper ring 2e.

As stated above, the female die 2 is allowed to reach a predetermined distance from the pressure bush 8 before the abutment faces 45 come into abutment with the abutment faces 30. This distance may be adjusted to any desired value by adjustment of the turnbuckle links 34. In many cases it will be necessary to adjust the turnbuckle links 34 so that the said distance is equal

to the original thickness of the blank, so that the abutment faces 45 and 30 come into contact at the same moment as the metal blank is contacted by the draw-ring 2c and gripped between the latter and the pressure bush 8. The portion of the metal blank gripped between the parts 2c and 8 tends to thicken during the initial drawing, and the above-described adjustment limits the pressure exerted on the blank by the parts 2c and 8 to a permissible value.

On the return stroke motion is imparted to the former spindle in the opposite direction to the ram, through the links 34, inclined abutment faces 46, 31, members 36, rack members 25, pinions 18 and member 14. As the former 9 is retracted from the female die, the extruded metal container abuts against the stripper ring and is positively stripped from the former and falls from the female die through the window 2b when the former has been sufficiently retracted.

When the ram reaches a predetermined point in its return stroke, where the working end 9a of the former 9 is about to leave the female die 2, the rollers 48 roll down the ramps 47, the inclination of the abutment faces 46 on the member 36 and the abutment faces 31 on the rack members 25 urges the members 36 out of engagement with the rack members 25. Thereafter, the former is urged away from the female die and the pressure plate 12 together with the pressure bush 88 are urged towards the ram by the springs 41, until the ram again is at the top of its stroke and in the rest position, thus completing the cycle of operations.

The above-described arrangement provides for a first drawing operation by means of the draw-ring 2c, followed by a reducing or extruding operation by means of the reducing ring 2d. If it is desired to perform a second reducing operation, the exchangeable female die 2 may be replaced by a female die 102 (Fig. 5) having a draw ring 102c followed by two spaced reducing rings 102d and a stripper ring 102e. The stroke of the ram 1 must be correspondingly lengthened, and the working end 9a of the former must be exchanged for a correspondingly larger working end.

What I claim is:

1. A press for the deep-drawing of sheet metal comprising a frame, a ram mounted for reciprocation in said frame, a female die carried by said ram, said ram being mounted in said frame for reciprocation co-axially of said female die with a working and a return stroke, a bearing fixed in said frame co-axially of said female die, a former spindle slideable in said bearing into and out of said female die during said working and return strokes respectively, an annular member slideably mounted on said former spindle and co-operating with said female die, a transmission member adjustably mounted on said former spindle, rack-and-pinion means operatively connecting said transmission member with said former spindle to convert sliding motion of said transmission member into equal and opposite sliding motion of said former spindle, a pair of adjustable-length links pivotally attached to said ram and swingable into and out of engagement

with said transmission member, a first abutment face on each link and a corresponding first abutment face on said transmission member which co-operate during the working stroke, a second abutment face on each said link and a corresponding second abutment face on said transmission member which co-operate during the return stroke, said second abutment faces being inclined to urge said links to disengage said transmission member, a pair of rollers mounted on said frame, and ramps on said links co-operating with said rollers to swing said links into engagement with said transmission member at a predetermined point of the working stroke and to hold said links in engagement until the corresponding point of the return stroke is reached.

2. A press for the deep-drawing of sheet metal comprising a frame, a ram mounted for reciprocation in said frame, a female die carried by said ram, said ram being mounted in said frame for reciprocation co-axially of said female die with a working and a return stroke, a bearing fixed in said frame co-axially of said female die, a former spindle slideable in said bearing into and out of said female die during said working and return strokes respectively, an annular member slideably mounted on said former spindle and co-operating with said female die, a pressure plate slideably mounted on said former spindle and bearing against said annular member, a pair of rack members connected to said pressure plate, a pair of pinions mounted on said frame and meshing with said rack members, a pair of racks carried by said former spindle and meshing with said pair of pinions, a pair of adjustable-length links pivotally attached to said ram and swingable into and out of engagement with said rack members, a first abutment face on each link and a corresponding first abutment face on each said rack member which co-operate during the working stroke, a second abutment face on each said link and a corresponding second abutment face on each said rack member which co-operate during the return stroke, said second abutment faces being inclined to urge said links to disengage said rack members, a pair of rollers mounted on said frame, and ramps on said links co-operating with said rollers to swing said links into engagement with said rack members at a predetermined point of the working stroke and to hold said links in engagement until the corresponding point of the return stroke is reached.

3. A press according to claim 2, including tension springs connecting the free ends of said links with said rack members.

CHARLES JOSEPH RHODES.
